(57) **CLAIM**

The ornamental design for portion of display screen with animated graphical user interface, as shown and described.

DESCRIPTION

FIG. 1 is a front view of a portion of a display screen with animated graphical user interface showing a first image in a sequence of a first embodiment of my new design;

FIG. 2 is a perspective view showing a second image in the sequence thereof;

FIG. 3 is a perspective view showing a third image in the sequence thereof;

FIG. 4 is a perspective view showing a fourth image in the sequence thereof;

FIG. 5 is a front view of a portion of a display screen with animated graphical user interface showing a first image in a sequence of a second embodiment of my new design;

FIG. 6 is a perspective view showing a second image in the sequence thereof;

FIG. 7 is a perspective view showing a third image in the sequence thereof; and,

FIG. 8 is a perspective view showing a fourth image in the sequence thereof.

The appearance of the images transitions sequentially between the images shown in FIGS. 1 through 4, and 4 through 1. The appearance of the images transitions sequentially between the images shown in FIGS. 5 through 8, and 8 through 5. The process or period in which one image transitions to another image forms no part of the claimed design.

The broken line showing of the outermost broken lines in each figure represents the outer periphery of the portion of the display screen, and is the boundary of the claimed design. The broken line showing of elements on the display screen illustrate portions of the article and form no part of the claimed design.
